CLAIM

The ornamental design for a holster for a handgun, as shown and described.

DESCRIPTION

FIG. 1 is a perspective view of a firearm holster showing my new design;

FIG. 2 is a front view thereof;

FIG. 3 is a right side view thereof;

FIG. 4 is a left side view thereof;

FIG. 5 is a back view thereof;

FIG. 6 is a second embodiment being the same as the first with the exception of the decorative pattern shown at the edge of the holster thereof;

FIG. 7 is a third embodiment being the same as the first with the exception of the decorative pattern shown at the edge of the holster thereof;

FIG. 8 is a top view thereof; and,

FIG. 9 is a bottom view thereof.
